UNITED STATES PATENT OFFICE.

JOHN G. LANNING, OF DETROIT, MICHIGAN, ASSIGNOR TO DETROIT LUBRICATOR COMPANY, OF DETROIT, MICHIGAN, A CORPORATION OF MICHIGAN.

FUELIZER.

Application filed January 15, 1921. Serial No. 437,539.

To all whom it may concern:

Be it known that I, JOHN G. LANNING, a citizen of the United States of America, residing at Detroit, in the county of Wayne 5 and State of Michigan, have invented certain new and useful Improvements in Fuelizers, of which the following is a specification, reference being had therein to the accompanying drawings.

10 The invention relates to fuelizers of that type in which a combustible mixture is burned and the products of combustion introduced into an engine intake to assist in the vaporization of the liquid fuel. It is the object of the invention to automatically control the quantity of heated products thus introduced according to the requirements of the engine and to this end the invention consists: first, in the construction for thermostatically controlling the operation of the fuelizer; and second, in various features of construction as hereinafter set forth.

In the drawings:

Figure 1 is a cross-section through a fuelizer of my improved construction;

Figure 2 is a vertical longitudinal section therethrough;

Figure 3 is a horizontal longitudinal section;

Figure 4 is a front elevation;

Figure 5 is a section through the thermostat.

The fuelizer to which my improvements are applied may be of any suitable construction, but as shown, A is a casing or fitting adapted to be inserted between the carburetor and manifold of an internal combustion engine. B is a conduit section formed within said fitting and forming a portion 25 of the intake. C is a jacket surrounding this conduit section and forming a combustion chamber, and D is a jacket surrounding the jacket C. At one side of the casing is an extension E forming an enlargement F of the combustion chamber and connected to this extension is the spark plug G. At one point the chamber between the jacket C and the conduit B is connected by a port H with the interior of the conduit B for the purpose of introducing gases into the intake. I is a baffle between the port H and the chamber F for compelling the products of

combustion to encircle the conduit B before passing through said port.

The combustible mixture is preferably obtained from the carburetor and is first introduced into the chamber between the jacket D and the jacket C. As shown, this is accomplished by a port J, which registers with a corresponding port K in the flange of the carburetor and connecting with the mixing chamber thereof. The combustible mixture, after passing through the port J encircles the jacket and finally passes into the chamber F where ignition takes place, the flame and products of combustion passing around within the inner jacket and the products 60 passing through the port H into the intake. In thus passing around the inner jacket, heat is communicated to the walls thereof 65 and to the incoming mixture in the outer jacket, so that the fuel thereof is vaporized 70 before introduction into the chamber F.

As has been stated, it is the object of the present invention to automatically control 75 the quantity of the products of combustion entering the intake, which is accomplished through a thermostat. As shown, this thermostat L, which may be of any suitable construction, is located adjacent to the port 80 for connecting the outer and inner jackets and this port is controlled by a valve M operated by the thermostat. Specifically, the port or ports N for connecting the outer and inner jackets are formed in a cylindrical member O, which is embraced by the cylindrical valve M. The thermostat L is affected by the heat communicated thereto from the casing A, the arrangement being such that with increase of heat, the valve M 85 is shifted to cut down the open area of the ports N, thereby diminishing the quantity of combustible mixture which can pass from the outer jacket to the combustion chamber F. Thus when the engine is first started 90 and the parts are all cold, there will be a relatively large area of opening in the ports N, so that the amount of combustible mixture which is ignited by the spark plug G is correspondingly large. This will rapidly 95 heat up the casing A, while the heated products of combustion will supply the requisite heat to the intake and as soon as properly heated, the thermostat L will cut down upon 100

the supply. In this way the quantity of mixture burned is regulated automatically, according to the requirements of the engine.

As shown in Figures 1 and 5, the thermostat 5 stat is in the form of a spiral P of composite metal, which will expand differentially and cause a rotation of one end of the spiral relative to the other. One end is anchored to the cylinder O, being attached thereto by a clamping screw Q, while the other end is attached to a sleeve M which constitutes the valve. This sleeve has a port R therein which normally registers with a series of ports N and upon the expansion of the spiral and rotation of the sleeve these ports will be gradually cut off. There is also a single port N' which is not controlled by the valve and which will furnish the minimum amount of combustible mixture required. The whole construction is enclosed in a hollow cap S, which has a threaded engagement with the casing A.

What I claim as my invention is:

1. A fuelizer comprising a combustion chamber, a connection between said combustion chamber and the intake of an internal combustion engine, a supply connection for combustible mixture, a valve for controlling said supply connection, and a thermostat 25 stat controlled by the temperature of said combustible mixture for operating said valve.

2. A fuelizer comprising a casing containing a combustion chamber, a conduit section surrounded thereby forming a portion of the engine intake, a port connecting said combustion chamber with said intake, a supply connection for combustible mixture to said combustion chamber, a valve 35 controlling said supply, and a thermostat mounted on said casing for operating said valve and controlled by the heat communicated thereto from said casing.

3. A fuelizer comprising a casing having an inner conduit section forming a portion of the engine intake, a jacket surrounding said conduit section forming a combustion chamber and a jacket surrounding said first-mentioned jacket, forming an inlet for 45 the combustible mixture, a spark plug for igniting the mixture within said combustion chamber, a valve for controlling the admission of mixture from said outer jacket to said combustion chamber, and a thermostat 50 for actuating said valve.

4. A fuelizer comprising a casing containing a combustion chamber, a conduit section forming a part of the engine intake disposed within the combustion chamber, 60 means for supplying a combustible mixture between the casing and combustion chamber, thermostatic means for controlling the supply of the mixture to the combustion chamber, a spark plug for igniting the mixture in the chamber, means for introducing

the products of combustion into the conduit section, and a baffle located in the combustion chamber opposite the spark plug for compelling the products of combustion to encircle the conduit before being introduced 70 therein.

5. A fuelizer for internal combustion engines comprising a casing containing a combustion chamber, a conduit section forming a part of said engine intake disposed within the combustion chamber, means for supplying a combustible mixture between said casing and chamber, thermostatic means for controlling the supply of mixture to said chamber, ignition means within said chamber, 75 means for introducing the products of combustion into said conduit section, and means for compelling the products of combustion to pass around said conduit section before being introduced therein. 80

6. A fuelizer for internal combustion engines comprising a casing, a jacket within said casing, means for supplying a combustible mixture to said casing, said jacket being in communication with said casing, 85 thermostatic means for controlling the passage of combustible mixture to said jacket, ignition means in said jacket, and means for introducing the products of combustion into said engine intake. 90

7. A fuelizer for internal combustion engines comprising a casing, a jacket within said casing, means for supplying a combustible mixture to said casing, said jacket being in communication with said casing, 95 thermostatic means for controlling the passage of combustible mixture to said jacket, ignition means within said jacket, means for compelling the products of combustion to pass around the walls of said jacket to heat 100 the combustible mixture in said casing, and means for introducing the products of combustion into said engine intake. 105

8. A fuelizer comprising a casing containing a combustion chamber, a conduit section surrounded thereby forming a portion of the engine intake, a port connecting said combustion chamber with said intake, a jacket surrounding said combustion chamber, means for supplying a combustible mixture between said combustion chamber and said jacket, a supply connection for combustible mixture to said combustion chamber, a valve controlling said supply, 110 and a thermostat mounted on said casing 115 for operating said valve and controlled by the heat communicated thereto from said casing. 120

9. A fuelizer comprising a casing containing a combustion chamber, a conduit section surrounded thereby forming a portion of the engine intake, a port connecting said combustion chamber with said intake, a jacket surrounding said combustion chamber, means for supplying a combustible 125 mixture to said combustion chamber, 130

mixture between said combustion chamber and said jacket, a supply connection for combustible mixture to said combustion chamber, means for igniting the combustible mixture in said combustion chamber, means for directing the products of combustion around said intake to vaporize the combustible mixture between said combustion chamber

ber and said jacket, means for controlling said supply connection to said combustible chamber and thermostatic means for operating said valve controlled by the heat communicated thereto from said casing.

In testimony whereof I affix my signature.

JOHN G. LANNING.
